UNITED STATES PATENT OFFICE.

JAMES MACPHAIL, OF BLUE ISLAND, ILLINOIS, ASSIGNOR TO THE PLANO MANUFACTURING COMPANY, OF CHICAGO, ILLINOIS.

GRINDING-WHEEL CENTER.

SPECIFICATION forming part of Letters Patent No. 662,240, dated November 20, 1900.

Application filed March 11, 1899. Serial No. 708,741. (No model.)

To all whom it may concern:

Be it known that I, JAMES MACPHAIL, a resident of Blue Island, in the county of Cook and State of Illinois, have invented certain new and useful Improvements in Grinding-Wheel Centers, of which the following is a specification.

The object of my invention is to provide a novel, simple, and efficient grinding-wheel center comprising means for removably securing the grinding-wheel to its shaft or arbor or to a sleeve to be removably attached to a driving-shaft.

My invention pertains to the many kinds and sizes of grinding-wheels—such as emery-wheels, common grindstones, and the like—and has useful application to those grinding-machines where it is necessary or desirable to quickly remove a grinding-wheel and substitute another on the same driving-shaft.

In the accompanying drawings, Figure 1 is a front elevation of a grinding-wheel with my center or attachment applied; Fig. 2, a section on line 2 of Fig. 1; Fig. 3, a section on line 3 of Fig. 2, and Fig. 4 a view of the sleeve with the wheel removed.

The grinding-wheel 1 may be any of the ordinary grinding-wheels. It is designed to be attached to a rotatable sleeve, which may be 30 in turn removably attached to a driving-shaft in the following novel manner: The member or sleeve 2 is a hollow cylinder having at its central part a portion 3 of increased diameter and provided with longitudinal grooves 4 and 35 grooves 4^a at right angles to the longitudinal grooves. These latter grooves are preferably dodged, as shown. The sleeve is also provided with one or more sets of pin-holes 5. When the wheel is designed to be removable, 40 together with immediate fastening devices or center, it is made hollow, as shown; but if not the sleeve may become the arbor or driving-shaft itself and may then be made solid.

The driving-shaft 6 is adapted to be driven 45 in any suitable and well-known manner and is provided with one or more pin-holes 7, depending on the number formed in the sleeve. Cotter-pins 8 or other suitable devices enter the holes 5 and 7 and secure the shaft and 50 sleeve together.

The wheel has a central opening to fit snugly

on the portion 3, and when in proper position suitable material is either poured or forced in the grooves 4 and 4^a, thereby securely fastening the wheel to the sleeve and preventing lateral movement thereon. An efficient method is by leading.

When it is desired to remove the wheel and its center or attachment, so as to substitute another wheel, the cotters are removed and 60 either the shaft or wheel moved laterally and the other wheel can then be readily attached in the same manner.

Although I have described more or less precise forms and details of construction, I do not 65 intend to be understood as limiting myself thereto, as I contemplate changes in form, the proportion of parts, and the substitution of equivalents, as circumstances may suggest or render expedient, and without departing from 70 the spirit of my invention.

I claim—

1. In a grinding-wheel holder comprising a sleeve having an enlarged portion on which the grinding-wheel is rigidly and permanently 75 fixed, a driving-shaft inside the sleeve, and means for detachably securing the sleeve to the shaft.

2. A grinding-wheel holder comprising a sleeve having pin-holes near its ends and also 80 having an enlarged portion provided with longitudinal grooves to be filled with a material to permanently secure the grinding-wheel on such sleeve, a driving-shaft having pin-holes registering with the pin-holes in the 85 sleeve and removable pins entering both sets of holes.

3. A grinding-wheel center or holder comprising a sleeve having a pin-hole, a grinding-wheel received on the sleeve, means for 90 fastening the wheel on the sleeve, a driving-shaft having a pin-hole and a pin entering both said pin-holes.

4. A grinding-wheel holder comprising a member having an enlarged portion provided 95 with longitudinal grooves, a grinding-wheel received on said portion and a material forced into said grooves and within the wheel.

5. A grinding-wheel holder comprising a member having an enlarged portion 3 provided with grooves 4 and a grinding-wheel 1 received on said member.

6. A grinding-wheel holder comprising a sleeve 2 having a pin-hole 5 and also having an enlarged portion 3 provided with longitudinal grooves 4, a grinding-wheel 1 received on the enlarged portion of the sleeve and secured thereto by material forced into the grooves and within the wheel, a driving-shaft 6 having a pin-hole 7 and a cotter-pin 8 entering holes 5 and 7 to secure the sleeve to the shaft.
7. A grinding-wheel center comprising a member provided with longitudinal and cross grooves, a grinding-wheel and filling material in said grooves for securing the wheel on said member.
8. A grinding-wheel center comprising a member having an enlarged portion provided with longitudinal and cross grooves and a grinding-wheel received on said member.
9. A grinding-wheel center comprising a member having an enlarged portion provided with longitudinal grooves and also with dodged cross-grooves between said longitudinal grooves and a grinding-wheel received on said member.

JAMES MACPHAIL.
